UNITED STATES PATENT OFFICE.

JOHN HERSON, OF PORT HURON, ASSIGNOR TO SIDNEY COLE, WILLIAM H. BURGESS, FRANK MCKENNEY, AND JAMES H. MCKENNEY, ALL OF CROSWELL, MICHIGAN.

ATTACHMENT FOR FANNING-MILLS.

SPECIFICATION forming part of Letters Patent No. 451,670, dated May 5, 1891.

Application filed March 7, 1891. Serial No. 384,065. (No model.) Patented in Canada September 4, 1886, No. 24,883; in Austria-Hungary March 31, 1887, No. 76,667, and in Belgium June 29, 1887, No. 14,827.

To all whom it may concern:

Be it known that I, JOHN HERSON, a citizen of Canada, residing at Port Huron, in the county of St. Clair and State of Michigan, have invented certain new and useful Improvements in Attachments for Fanning-Mills, (for which I have obtained patent in Canada, No. 24,883, September 4, 1886; in Belgium, No. 14,827, June 29, 1887, and in Austria-Hungary, No. 76,667, March 31, 1887;) and I do declare the following to be a full, clear, and exact description of the invention, such as will enable others skilled in the art to which it appertains to make and use the same, reference being had to the accompanying drawings, and to the letters of reference marked thereon, which form a part of this specification.

The object of my invention is to provide a very simple and efficient device by the use of which all impurities will be removed from a mass or mixture of grain and the grain separated into its different grades or kinds by a single operation and to accomplish this object by means that are not complicated and liable to get out of order. These objects I accomplish by the use of the mechanism illustrated in the annexed drawings; and the invention consists in certain novel features of the same, as will be hereinafter more fully set forth, and particularly pointed out in the claim.

In the drawings referred to, Figure 1 is a rear elevation of a fanning-mill provided with my improvements. Fig. 2 is a longitudinal vertical section of the same, and Fig. 3 is a detail perspective view of the shoe and the tapper.

The casing A or frame of the mill is of the usual or any preferred construction, and the fan B is mounted in the front end thereof in the usual manner.

A hopper C is arranged in the top of the frame, and the grain is placed in this hopper when the mill is to be operated, as will be readily understood.

In the drawings I have shown a slide D mounted on the under side of the top of the frame so as to cover or uncover the opening in the hopper at will; but it is obvious that

this slide is not essential and forms no part 50 of my invention.

Within the frame and near the rear end of the same I provide a gang E of sieves or screens, which consists of the side plates F and the sieves or screens G, secured between them. This gang of sieves is hung within the frame, so as to have a slight vibration by means of the straps H, having their upper ends secured to the inner sides of the side walls of the frame and their lower ends secured to the side plates of the gang near the lower edges thereof.

At the upper end of the gang of sieves I arrange a deflector or slide I, which is inclined toward the rear end of the gang, and is adapted to extend under the opening of the hopper so as to cause the grain to run downward toward the rear end of the gang of sieves as it comes from the hopper. Below the deflector or slide I provide a sieve or screen J, which is arranged at a less pronounced inclination than the slide or deflector, and has its rear end projecting beyond the rear end of the frame or gang and provided with a spout or oat-arrester K, as shown. The chaff contained in the grain will be blown over the end of the sieve and the spout by the current from the fan, and the oats will be deposited in the spout and thereby carried to one side and collected. It will 80 consequently be understood that this screen with the spout is used only when it is desired to remove oats from the wheat and at the same time grade the wheat.

Below the sieve or screen J and at the rear end of the gang I provide the substantially parallel screens or sieves L M, which are inclined downward toward the front end of the gang. These screens are of different meshes, the upper one being the larger, and also of 90 different sizes, the lower one being the shorter. These substantially parallel screens or sieves are arranged adjacent to and above a metallic shoe N, which forms the bottom of the gang or screen frame. This shoe is provided 95 at its front end with the delivery-spouts O P Q, which extend in opposite directions, and are adapted to convey the different qualities

or kinds of grain to the proper receptacles. The foremost spout receives the grain which fails to pass through the screen or sieve L, the intermediate spout receives the grain 5 that passes over the end of the screen or sieve M, and the rearmost spout receives the grain that drops through the sieve M and falls onto the shoe.

The sieve M is the finest sieve or screen of 10 the lot, and consequently the grain that passes therethrough will be of the finest grade. In order that none of this grain may be lost by failing to pass through the sieve, I provide a tapper R, which consists of a rock-shaft S, 15 mounted in suitable bearings on the shoe, and the striker-arms T, extending laterally therefrom. A pulley U is provided at the rear end of the rock-shaft, and a belt or band V is passed tightly over this pulley and then 20 downward through the rear end of the shoe, after which its ends are crossed and secured rigidly to the rear end of the casing or frame of the mill, as clearly shown in Figs. 1 and 3.

The fan and the gang of sieves are operated 25 in the usual manner, the sieves being vibrated transversely of the mill. As the gang of sieves is thus caused to swing from side to side of the mill, the pulley U will be forced to travel under the belt or band passed there- 30 over, and consequently the rock-shaft will be oscillated, and the striker-arms caused to impinge against the bottom sieve or screen, and thus loosen the grain thereon, so that none of it can collect. All of the grain will thus be 35 agitated and the finest grade made to pass through the sieve onto the shoe, whence it passes to the proper receptacle, as will be readily understood from the foregoing description taken in connection with the an- 40 nexed drawings.

It will be noticed upon reference to the drawings that the lower screens have their front ends resting upon transverse partitions, so that none of the grain that passes 45 over their front ends can mingle with that which passes through their meshes, thus insuring the maintaining of the separated grains in distinct lots.

It will be seen from the foregoing descrip-

tion, taken in connection with the accompanying drawings, that I have produced an extremely cheap, simple, and efficient device by the use of which all impurities will be removed from the grain and the grain separated into its several component grades or 55 kinds at a single operation. The several parts of my improved mill are arranged in a very compact manner, and at the same time they are readily accessible for the purposes of cleaning or repairing. The shoe employed 60 by me presents in a single element a bottom for the gang of sieves and also delivery-spouts for the several grades or different kinds of grain in the mixture, all of which, except the one delivered by the spout K, are 65 delivered to their proper receptacles by the shoe. The tapper at the rear end of the shoe is a very important element of my invention, as it positively prevents any grain collecting 70 on the bottom screen or sieve and clogging the meshes thereof, and is automatic in its operation. Each screen or sieve in my mill serves to separate one grade or kind of grain from the mass and deliver it to the proper delivery-spout. It is my intention in prac- 75 tice to furnish in each mill a series of sieves of different sizes and meshes, so that the owner can quickly arrange the mill for separating any kind of grain into its several 80 grades, or for separating the different kinds of grain from each other and from the impurities when mingled.

Having thus described my invention, what I claim, and desire to secure by Letters Patent, is—

The combination, with the casing and the gang of sieves, of the shoe forming the bottom of the said gang, the tapper mounted on said shoe and provided with a pulley at its rear end, and the belt or band passed over 90 the said pulley and having its ends crossed and secured to the casing, as set forth.

In testimony whereof I affix my signature in presence of two witnesses.

JOHN HERSON.
